UNITED STATES PATENT OFFICE.

HORACE E. BROWN AND CLARENCE L. JOHNSTON, OF OAKLAND, CALIFORNIA.

MECHANISM FOR INTERLEAVING SHEETS.

1,228,400.

Specification of Letters Patent. Patented June 5, 1917.

Application filed December 15, 1913. Serial No. 806,732.

To all whom it may concern:

Be it known that we, HORACE E. BROWN and CLARENCE L. JOHNSTON, both citizens of the United States, both residing at Oak-
5 land, in the county of Alameda and State of California, have invented new and useful Improvements in Mechanism for Interleaving Sheets, of which the following is a specification.

10 This invention relates to a machine for cutting, folding, interlocking and stacking paper, and involves means especially for interlocking paper fed from a plurality of continuous rollers.

15 It is the object of the present invention to provide a practical machine of maximum capacity capable of drawing material from a plurality of rolls of stock and cutting, folding, interlocking and packaging 20 the cut sheets; and it is a particular object of the present invention to provide a machine for manufacturing paper towels, toilet paper and the like, economically and rapidly and giving each sheet a reinforcing 25 marginal fold.

The invention consists of the parts and the combination and construction of parts as hereinafter more fully described and claimed, having reference to the accompanying drawings, in which—

Figure 1 is a perspective view of one of the folded sheets or leaves, partly open.

Fig. 2 shows diagrammatically a stack of the sheets as produced by the machine.

35 Fig. 3 is a plan view of the mechanism with parts in section.

Fig. 4 is a vertical longitudinal section.

Fig. 5 shows diagrammatically the method of alternate interlacing of the sheets.

40 In Fig. 1 there is shown a towel or sheet such as is produced by the present novel machine, each sheet comprising when folded a top leaf a and a lower leaf a' connected along the fold a^2 ; the outer edge of the bottom leaf a' being folded outward at a^3 to form a transversely extending narrow flap marginal reinforcing part a^4 ; the three folds a , a' and a^4 being arranged in zigzag.

45 As shown in Fig. 2, the leaves are stacked by the present machine in such fashion that between the leaves a and a' of one sheet and adjacent to the fold a^2 thereof, there is interfolded a leaf b^2 of the next sheet, whose fold b^2 is at the opposite side of the stack 55 from the fold a^2 of the first sheet; in other words, the machine will produce a stack of

sheets designated for the purpose of identification as A and B, with all of the folds a^2 at the left of the stack, while all of the folds b^2 will be at the right of the stack, 60 as viewed in Fig. 2, the sheets in the stacks A—B being otherwise folded identically.

A stack of sheets thus interfolded is generally dispensed from a suitable holder not 65 here shown, whereby the bottommost leaf a^1 of a sheet with its marginal edge a^4 is exposed. As the sheets are used from the bottom, the sheet removed from the stack draws out therefrom the next interlocked 70 leaf or portion of the succeeding sheet. The present machine is designed to fold and interleaf these sheets where they are to be used as paper towels, and the sheets are necessarily of considerable size. 75

It is to produce these towels, cut, folded and stacked in the manner above described, that we have devised the present machine. 80 2 is a suitable frame structure in which is appropriately mounted a pair of opposed cylinders 15—16 having respective shafts 14—17. The paper webs from which the respective sheets A—B are to be cut, are indicated at C—D and come from any suitable source and fed and tensioned by 85 any appropriate means. Shaft 14 is driven from any suitable source of power. It carries a gear 13 meshing a gear 18 of similar proportions, so that the two cylinders 15 and 16 operate at uniform speed in opposite directions; their peripheries being in such juxtaposition between the shafts 14 and 17 as to permit the paper drawn from the stock to pass therebetween.

90 Mounted longitudinally in and projecting beyond the circumference of each of the cylinders 15 and 16 are fixed adjustable folder blades 21, of which there are two in each cylinder, and being diametrically set in their respective cylinders and the cylinders so set that their blades are at a position 90° to the blades of the opposite cylinder, so that during a complete revolution of the two geared cylinders first one and then the other of the folder blades 21 will be 95 alternately projected across the diametral plane between the axes of the shafts 14—17. For the clearance and entrance of the blades 21 into the coöperating portions of the opposite cylinders, these latter are provided 100 with diametrically opposite longitudinal slots 22 which are timed to register accu-

5 rately with the projecting blades 21 as the latter rotate, and thus as the paper webs C—D are fed to and drawn around by the cylinders 15—16 the paper will be projected by one of the folder blades 21, Fig. 4, into the slot 22 of the adjacent portion of the opposite cylinder, as shown. The paper is then grasped by suitable grippers 23 mounted in the respective cylinders 15—16 10 and operable in the slots 22 and diametrically opposed in their respective cylinders; the grippers being mounted in the rocker shafts 25 and normally maintained closed by springs 24. The outer edges of the grippers are rounded to permit a blade 21 with the overfolded web to enter; the grippers being automatically thrown by the spring 24 into pinching, clamping and creasing engagement with the stock folded over the 15 longitudinal edge of the interposed folder blade 21, where it lies in the slot 22.

As the cylinders 15—16 rotate, one of the folder blades 21 from one cylinder, as 16, will project into the registered slot 22 to 20 force the paper therein whereupon it will be clamped by the grippers 23 and carried by this during the rotation of the cylinder 15 downwardly in the direction of the arrow c, and when the cylinder is turned a 25 quarter revolution the next folder blade 21, in this case on cylinder 15, will be carried into registration and project into the approaching longitudinal slot 22 on the cylinder 16; whereupon the grippers 23 in the 30 cylinder 16 into which the folder blade 21 has projected will automatically operate to pinch and clamp the paper, the continued rotation of the cylinder 16 carrying the closed clamp downward in the direction of the arrow d, thus carrying the folded portion 35 of the stock to the left of the stock, as shown; the alternate deposits of the folds continuing so long as the machine is in operation and paper fed to the rolls. This 40 alternate positioning of the folds of the stock would occur irrespective of whether there would be feeding into the machine paper from one or the other, or both sides thereof.

45 For the purpose of automatically and positively releasing the folded and creased stock, the ends of the gripper rock-shafts 25 are provided with levers 26, carrying cam rollers 27, these rollers being thrown in one direction by suitable fixed cams 28 on the frame 2 to release the grippers 23 from the folded paper at the proper time, so that the folded material can be readily cleared from the cylinders by stripper blades 29 which lie 50 in grooves 30 formed for their reception in the circumferences of the cylinders 15—16, the stripper blades 29 forming the upper terminals of a curved chute structure 31, in which the folded stock is accumulated and 55 conveyed to a suitable discharge position.

It is an important object of the present invention to provide a machine which is capable of severing the in-feeding webs of paper in a suitable manner and order so that interlaced sheets as before described, will be produced, and to that end there are provided and co-operating with the cylinders 15—16 suitable cutter heads 35 which are fast on shafts 36, suitably journaled in the frame 2, and one of the shafts 36 has secured on one end an actuating gear 37 of suitable proportions to and engaging with the cylinder gear 13, while to the opposite end of the other shaft 36 is secured an actuating gear 38 engaging a gear 39 provided for its engagement and mounted upon the shaft 17; the purpose of placing the gears 37—38 at opposite ends of their respective shafts being to permit closer mounting of their respective shafts.

55 The cutter heads 35 are each diametrically oppositely provided with fixed longitudinal cutter blades 40, one of which is shown in Fig. 4 as moving into registration with a longitudinal complementary slot 41, here shown as formed between removable jaws 42 which may be mounted in a removable insert 43 fitted in and secured to the cylinder 15.

Each of the cylinders 15 and 16 is provided at opposite sides with the jaw members 42, forming the cutter receiving slots 41, one of the slots at each revolution of the cylinder registering with the co-operating blades 40 of the coacting cutter head 35, so that as the blade 40 enters the slot 41 the paper is cut transversely, the grain of the stock preferably running longitudinally of the stock and being cut transversely by the cutter 40. Each of the cutter blades 40 is flanked on one side by a longitudinally extending cushion 44 designed to clear the projecting edge of the contiguous folder blades 21 and serving to hold the paper down upon the surface of the cylinder along the edge of the slot 41, while the cutter 40 is entering and severing the paper. On the opposite side of the cutter blade 40 from the side on which the cushion members 44 are mounted, there are provided suitable strippers 45 operating to clear the adjacent end of the severed stock from the cutter 40 as this revolves.

In order that neither of the entering webs C—D is dropped from the cylinders 15—16, after it has been severed by the cutters 40, there are provided a suitable number of movable pins 46 spaced longitudinally across the length of the cylinders and movable in the jaw 42, the pins being so disposed with relation to the cutter slot 41 that after the paper is severed by the cutter the pins 46, which are at that time projected, will enter the following and adjacent end of the stock and during the continued rotation of 130

the cylinders draw the paper around. As the projected pin retaining devices or pins 46 are retracted, as is shown in the cylinder 16, so as to release the paper held on its cylinder and coincidentally with the retraction of the retainer pins 46 which draw the end of the paper down toward the diametral plane of the shafts 14—17, and as the grippers 23 are drawn into clamping engagement with the inwardly folded stock, as in Fig. 4, another set of pins 48, which are mounted in appropriate arms 49 secured on the gripper rocker shafts 25, are projected through the cylinders as 15 to pick up the end of the paper which the retracted pins 46 release so that the loose or leading end of the paper from the cylinder 16 will be drawn around the lower quarter surface of the cylinder 15.

As the fold of paper or towel is released by the grippers 23 the following end of the towel on the upper quarter surface of the cylinder 15 and lying between the folder blade 21 of the cylinder 16 and the cutter 40 of the cylinder 15 will be carried to the right, as at arrow c, and the loose or trailing end behind the grippers 23 will fold over the leading end from the cylinder 16, which has been picked up by the draw pins 48 and will be released by these pins when the grippers 23 move downwardly the predetermined distance and are released by the action of the cam 28 upon the gripper lever 26, operating to lift the grippers 23 from the fold of the stock.

Any suitable mechanism may be utilized to project and retract the pins 46 for picking up the leading ends of the stock from the rolls, and in the present instance this mechanism comprises roller shafts 50, of which there are two mounted in each cylinder, these shafts being provided with rocker arms 51 in the outer ends of which the pins 46 are suitably mounted, the pins projecting through apertures 52 formed for their reception in the contiguous portions of the insert members 43.

The rocker shafts 50 are each provided at one end with a lever 53, carrying a cam roller 54 which is adapted to engage during its cycle with its cylinder, a fixed suitable cam 55 set to throw the lever 53 to rock the shaft 50 and retract the draw pins 46 at the proper time in the operation.

Thus it will be seen that the length of each towel section as it is severed from the in-feeding web of stock is about equal to one-half of the circumference of the cylinder or drum 15 or 16, over which it is drawn into the machine; and it will be further seen that while a portion of the stock in being severed at the top of the cylinders or drums 15—16 by the coöperation therewith of the cutter blades 40 of the slots 41, coincidentally therewith the approximate central portion of the strip at the moment of

being cut at the top is being folded by the coöperation of the projecting folder blade 21 of one cylinder entering the slot formed for its reception in the contiguous portion of the other cylinder, so that, in other words, each towel is folded transversely and approximately one-half of its length.

By providing the folding devices in quarter positions upon the opposite drums 15—16, first one section of the towel will be folded at the bight of one of the grippers 23 of one cylinder, and this bight drawn, as in Fig. 4, downward to the right and released while the next succeeding towel is transversely folded to form a bight by the opposite cylinder or drum by its respective acting gripper, to carry the bight or fold of the towel to the left; this alternate disposition and folding of the towel sections progressing constantly as a stack of towels is produced.

By disposing the projecting edge of the folder blades 21 in advance of the knife receiving slots 41 when the knife severs the paper behind the folding blades, and the folding blades move down into coöoperative relation with the adjacent slot 22 of the other cylinder, the short lap a^4 of the towel will be formed by the short remainder of the towel section existing between the edge of the folder blade 21 and the edge of the towel when the folder blade 21 enters the adjacent slot 22 and the stock is pinched by the grippers 23; it being remembered that the folder blade 21 at the same time that it folds the trailing end of the stock which has been cut at the slot 41 also folds the next following towel from the opposite cylinder midway its length and thus as the double folded stock is carried by the grippers downwardly in the direction of the arrows c or d, respectively, so accordingly will the bight or fold a^2 or b^2 inclose the narrow lap a^4 or b^4 .

It is manifest that the details of construction may be varied without departing from the principle of the invention.

Having thus described our invention what we claim and desire to secure by Letters Patent is—

1. Mechanism for interfolding sheets, which consists in the combination of a pair of cylinders arranged parallel to each other, gripper means carried by said cylinders for alternately folding web sections so that each section is folded once upon itself, with one leaf of one section interleaved with the two leaves of another section, means coöoperative with the cylinders for cutting the webs, and feed means for engaging the leading ends of the severed webs.

2. Mechanism for interfolding sheets, which consists in the combination of means for simultaneously feeding a plurality of webs, with means for cutting the webs into sections of uniform lengths including re-

4
tractile means to bring the cut sections together so that the end of one section is proximate to the middle of the opposite section, and means carried by the feeding means for folding the overlapping sections so that each section when folded incloses in its fold approximately one-half of another sheet.

3. Mechanism for interfolding sheets, which consists in the combination of means for simultaneously feeding a plurality of webs, with means for cutting the webs into sections of uniform lengths, with the end of one section proximate to the middle of the opposite section, means for folding the overlapping sections so that each section when folded incloses in its fold approximately one-half of another sheet, and coördinate means on the feed means for forming a narrow edge fold on one leaf of each section.

18 4. A mechanism for automatically interfolding webs and arranging the folded webs with their folds in zigzag relation, comprising a pair of uniformly moving drums set parallel with their adjacent faces in close juxtaposition, said drums being provided, respectively, with independently movable male and female parts adapted to register during the operation of the drums for the alternate folding of the in-feeding webs,

25 first in one cylinder and then in the other, and means for transferring the portion of one web adjacent the fold from one drum to the other.

5. A mechanism for automatically interfolding webs and for arranging the folded webs with their folds in zigzag relation, comprising in combination a pair of uniformly moving drums set parallel and with their adjacent surfaces in close juxtaposition, said drums being provided, respectively, with male and female parts adapted to register during the operation of the drums for the alternate folding of the infeeding webs, first in one cylinder and then in the other, means for severing the webs, and means movably mounted on the drums for engaging the leading ends of the severed webs.

6. In a machine for interleaving and folding in zigzag order in-feeding webs of stock, the combination of uniformly revolving juxtaposed drums carrying coöperative receiving gripping and carrying means for folding the webs, first in one cylinder and then in the opposite, cutting devices for coöperating with respective drums for severing the webs in antecedent position with relation to the folding operation, and positively actuated means for picking up the severed, advance end of the in-feeding stock and carrying it around with the drum to the folding mechanism of the drums.

7. In a machine for interleaving and folding in zigzag order infeeding webs of stock, the combination of uniformly revolving juxtaposed drums with coöperative re-

ceiving means for folding the webs, first in one cylinder and then in the opposite, cutting devices for coöperating with respective drums for severing the webs in antecedent position with relation to the folding operation, means for picking up the severed, advance ends of the in-feeding stock and carrying them around to the folding position of the drums, automatically operating grippers for clenching the folded ply of the webs and drawing the same alternately around one cylinder and then the other, and strippers for clearing the folded webs and delivering them into a discharge chute.

8. A mechanism for severing and folding webs and alternately distributing the folds in a pile, comprising in combination cylinders disposed with adjacent faces in close juxtaposition and revolving at uniform speed, said cylinders carrying a plurality of circumferentially spaced coöperating mechanisms for folding and gripping simultaneously in-feeding webs, and rotary cutting devices coöperating with complementary portions of the drums for cutting the webs in proper time, the axes of said cutters being disposed at an angle of less than 90° to each other.

9. A mechanism for severing and folding webs and alternately distributing the folds in a pile, comprising in combination cylinders disposed with adjacent faces in close juxtaposition and revolving at uniform speed, said cylinders carrying a plurality of circumferentially spaced coöperating mechanisms for folding and gripping simultaneously in-feeding webs, and rotary cutting devices coöperating with coördinate portions of the cylinders for cutting the web in proper time, said cutting devices and the folding mechanisms being so disposed relatively to their respective cylinders that the webs are cut into sections which are folded alternately at their central portions on one cylinder and then on the other, the principal fold of each section being made adjacent to the longitudinal center thereof and the trailing end of each preceding section being simultaneously folded with and in the central fold, for forming a narrow transverse lap or flange.

10. In a paper cutting, folding and arranging mechanism, the combination of uniformly revolving drums, rotary cutters being so disposed relatively that they alternately operate to cut from in-feeding web stock sections of a length approximately one-half the circumference of each drum, automatically operating pick-up means on each drum for engaging the in-feeding ends of the web stock as the stock is severed by the cutters, folding blades on each drum located slightly in advance of the cutting means of the drums, recesses formed in said drums for registration with the folding

- blades of the opposite drums and into which the recesses the trailing ends of the cut sections will be projected and into which the underlying section on the drum will be folded so as to include in the fold the trailing edge of stock on the opposite drum, and automatically operating means on each drum for transferring the leading edge of the stock on the opposite drum as it is released by the pick-up means on said drum.
11. An apparatus for cutting, folding and arranging sections of in-feeding web stock from a suitable source, comprising in combination rotary parallel drums with surfaces in close juxtaposition and moving at uniform speed, cutting mechanism coöperating with said drums for alternately severing sections from the in-feeding web stock, said sections being of a length approximately one-half the circumference of a drum, pick-up devices on each drum for engaging the in-feeding leading end of stock of its respective drum as it is severed by the coöperating cutter, folder blades attached to said drums in advance of the pick-up devices, the folder blades of one drum being adapted to transversely fold the cut section on the opposite drum at approximately its longitudinal center and simultaneously fold therewith the trailing edge of a section of paper on its own drum, and automatically operating grippers on the opposite drum for clutching the double folds of said sections and carrying the same away from the folding blade on the opposite drum.
12. An apparatus for cutting, folding and arranging sections of in-feeding web stock from a suitable source, comprising in combination rotary parallel drums with surfaces in close juxtaposition and moving at uniform speed, cutting mechanism coöperating with said drums for alternately severing sections from the in-feeding web stock, said sections being of a length approximately one-half the circumference of a drum, pick-up devices on each drum for engaging the in-feeding leading end of stock of its respective drum as it is severed by the coöperating cutter, folder blades attached to said drums in advance of the pick-up devices, the folder blades of one drum being adapted to transversely fold the cut section on the opposite drum at approximately its longitudinal center and simultaneously fold therewith the trailing edge of a section of paper on its own drum, and automatically operating grippers on the opposite drum for clutching the double folds of said sections and carrying the same away from the folder blade on the opposite drum, said grippers being timed on the drums to alternately clutch the folded stock so as to pile the cut and folded sections with the folds, first on one side and then on the other side of the pile, each drum having means for engaging the leading edge of stock on the opposite drum as these revolve, said means acting to transfer the leading edge of stock from the opposite drum to its own drum so that the leading edge will be interlaced between the central transverse fold of the section folded on its own drum.
13. An apparatus for cutting, folding and arranging sections of in-feeding web stock from a suitable source, comprising in combination rotary parallel drums with surfaces in close juxtaposition and moving at uniform speed, cutting mechanism coöperating with said drums for alternately severing sections from the in-feeding web stock, said sections being of a length approximately one-half the circumference of a drum, pick-up devices on each drum for engaging the in-feeding leading end of stock of its respective drum as it is severed by the coöperating cutter, folder blades attached to said drums in advance of the pick-up devices, the folder blades of one drum being adapted to transversely fold the cut section on the opposite drum at approximately its longitudinal center and simultaneously fold therewith the trailing edge of a section of paper on its own drum, and automatically operating grippers on the opposite drum for clutching the double folds of said sections and carrying the same away from the folding blade on the opposite drum.
14. An apparatus for cutting, folding and arranging sections of in-feeding web stock from a suitable source, comprising in combination rotary parallel drums with surfaces in close juxtaposition and moving at uniform speed, cutting mechanism coöperating with said drums for alternately severing sections from the in-feeding web stock, said sections being of a length approximately one-half the circumference of a drum, pick-up devices on each drum for engaging the in-feeding leading end of stock of its respective drum as it is severed by the coöperating cutter, folder blades attached to said drums in advance of the pick-up devices, the folder blades of one drum being adapted to transversely fold the cut section on the opposite drum at approximately its longitudinal center and simultaneously fold therewith the trailing edge of a section of paper on its own drum, and automatically operating grippers on the opposite drum for clutching the double folds of said sections and carrying the same away from the folder blade on the opposite drum, said grippers being timed on the drums to alternately clutch the folded stock so as to pile the cut and folded sections with the folds, first on one side and then on the other side of the pile.
15. An apparatus for cutting, folding and arranging sections of in-feeding web stock from a suitable source, comprising rotary parallel drums with surfaces in close juxtaposition and moving at uniform speed, cutting mechanism coöperating with said drums for alternately severing sections from the in-feeding web stock, said sections being

of a length approximately one-half the circumference of a drum, pick-up devices on each drum for engaging the in-feeding leading end of stock of its respective drum as it is severed by the coöperating cutter, folder blades attached to said drums in advance of the pick-up devices, the folder blades of one drum being adapted to transversely fold the cut section on the opposite drum at approximately its longitudinal center and simultaneously fold therewith the trailing edge of a section of paper on its own drum, and automatically operating grippers on the opposite drum for clutching the double folds of said sections and carrying the same away from the folder blade on the opposite drum, said grippers being timed on the drums to alternately clutch the folded stock so as to pile the cut and folded sections with the folds, first on one side and then on the other side of the pile, each drum having means for engaging the leading edge of stock on the opposite drum as these revolve.

16. In an apparatus for cutting, folding and piling paper sheets, the combination of uniformly rotating parallel drums disposed with surfaces in juxtaposition, folding blades on the drums, means on each drum for engaging and drawing in web stock from a suitable source, said stock-feeding means on each cylinder being disposed at an angle of 90° to similar means of the opposite drums, the drums being provided with slots into which the folder blades will project alternately during the rotation of the drums, cutter blades coöperating with respective drums for severing the in-feeding stock on a transverse line behind the folder blades so that sections of paper are produced, the folding mechanism successively operating to fold each section of paper transversely on a line about one-half the length of a section, the leading end of each section being interlaced with the preceding folded section when said section is folded transverse its central portion, and means for stripping the folded sections from the drums.

17. In a paper folding machine, a pair of coördinate adjacent rollers for folding the paper zig-zag fashion in severed sections, means on the rollers for folding each section intermediate its length, automatic transfer means on each roller for carrying the loose leading ends of the sections from one roller to the other, said means being operative by the rotation of the rollers, and comprising projectable and retractile pins, and automatic feed means for engaging the leading ends of the sections and drawing them around into position for action of the transfer means.

18. In a paper folding machine, a pair of coördinate adjacent rollers for folding the paper zig-zag fashion in severed sections, means on the rollers for folding each sec-

tion intermediate its length, automatic transfer means on each roller for carrying the loose leading ends of the sections from one roller to the other, said means being operative by the rotation of the rollers, and comprising projectable and retractile pins, and automatic feed means for engaging the leading ends of the sections and drawing them around into position for action of the transfer means, the feed means receding to clear the stock as the transfer means advances to engage the stock.

19. In a paper folding machine, a pair of coördinate adjacent rollers for folding the paper zig-zag fashion in severed sections, means on the rollers for folding each section intermediate its length, automatic transfer means on each roller for carrying the loose leading ends of the sections from one roller to the other, said means being operative by the rotation of the rollers, and comprising projectable and retractile pins, and automatic feed means for engaging the leading ends of the sections and drawing them around into position for action of the transfer means, the feed means receding to clear the stock as the transfer means advances to engage the stock, said feed means being operative by the rotation of the respective rollers.

20. A mechanism for automatically inter-folding webs and for arranging folded webs with their folds in zig-zag relation, comprising in combination a pair of uniformly moving drums set parallel and with their adjacent surfaces in close juxtaposition, said drums being provided, respectively, with independently movable male and female parts adapted to register during the operation of the drums for the alternate folding of the infeeding webs, first in one cylinder and then in the other, means for severing the webs, and means movably mounted on the drums for engaging the leading ends of the severed webs.

21. A machine for interleaving paper towels and the like comprising in combination, a pair of uniformly moving drums set parallel and close together, and adapted to receive overlapped sections of paper therebetween, and coöperating folding and carrying means within the respective drums by which each section is carried first partly around one drum and then partly around the other and folded upon itself, the leading and trailing ends of the sections being controlled.

22. A machine for interleaving paper towels and the like comprising in combination, a pair of uniformly moving drums set parallel and close together and adapted to receive overlapped sections of paper therebetween, and coöperating folding and carrying means within the respective drums by which the middle and both ends of each sec-

tion are controlled, and each section folded on a median line and embracing approximately one-half of a succeeding section before the sheets leave the cylinders.

23. A machine for interleaving paper towels consisting in the combination of a pair of parallel contiguous cylinders and means by which two webs of paper are fed between the cylinders in such relation that the webs may be brought together and separately severed into sections, with the severed edge of one section approximate to the mid-length of the complementary section, said cylinders having mutually coöperative self-contained devices for folding the sections successively so that approximately one-half of one section will be interleaved in the fold of a complementary section, said feeding and folding means controlling both ends of the cut sections during the folding operations.

24. In a machine for interfolding paper, the combination of a pair of coacting juxtaposed cylinders, for continuously receiving and feeding two webs of paper therebetween, and wrapping a portion of each web first around a portion of one cylinder and then around a portion of another cylinder, means for alternately severing the webs so that severed sections of the two webs overlap each other, movable means on the cylinders to cause each web section to be clamped and folded on approximately its median line, said feeding and folding means controlling both the leading and trailing edges of each section whereby the sections are properly interleaved.

25. In a machine for interleaving and folding paper towels or the like, the combination of a pair of coacting folding and interleaving cylinders having self-contained positively operated means to control the ends of the sections during the folding operations and to fold and clamp the sections each on a median line to inclose substantially one-half of each of two other sections.

26. In a machine for folding and interleaving paper towels and the like, the combination of a pair of coöperating cylinders adapted to receive towel sections therebetween in overlapped relation, and coöperating devices on the cylinders for controlling the middle and both ends of each section to interfold the sections with each folded section embracing a substantial part of another section.

27. In a machine for folding and interleaving paper towels and the like, the combination of a pair of coacting cylinders, means whereby overlapping towel sections are made to pass between the cylinders, devices on the cylinders for controlling the middle and both ends of each section to interfold the sections with each folded section embracing a substantial part of another sec-

tion and simultaneously to form a marginal terminal fold on each section.

28. In a machine for folding and interleaving paper towels and the like, the combination of a pair of coacting cylinders, means whereby towel sections are made to pass between the cylinders, devices on the cylinders for controlling the middle and both ends of each section to interfold the sections with each folded section embracing a substantial part of another section, said devices comprising lead pins and transfer pins on opposite sides of the devices for controlling the middle of the sections.

29. In a machine for folding and interleaving paper towels and the like, the combination of a pair of coacting cylinders, between which severed overlapping sections are adapted to pass, coöperating folding devices on the cylinders by which each section is folded on a median line, with a terminal edge of an overlapping section gathered in the said median fold, and means by which the loose terminals of the sections are transferred from one cylinder to another and the sections delivered from the cylinders with one section embracing substantially half of another section.

30. In a machine for folding and interleaving paper towels and the like, the combination of a pair of coacting cylinders, between which severed sections are adapted to pass, coöperating folding devices on the cylinders by which each section is folded on a median line, and means by which the loose terminals of the sections are transferred from one cylinder to another and the sections delivered from the cylinders interfolded with one section embracing substantially half of another section.

31. In a machine for interleaving and folding paper towels and the like, the combination of two coacting cylinders between which two webs of paper are adapted to pass, means coacting with the cylinders to sever the webs into sections so that the sections of one web overlap the sections of the other web, and positively operated means contained within the said cylinders for receiving and clamping the central portion of every web section to fold the same and with means on the cylinders to control the leading ends of each of the sections so that the sections are delivered folded and interleaved from the cylinders with each folded section embracing substantially one-half of another section.

32. In a machine for interleaving and folding paper towels and the like, the combination of two coacting cylinders between which two webs of paper are adapted to pass, means coacting with the cylinders to sever the webs into sections so that the sections of one web overlap the sections of the other web, and movable means for receiving

and clamping the central portion of every web section to fold the same and to control the trailing ends of each of the sections so that the sections are delivered folded and interleaved from the cylinders with each folded section embracing substantially one-half of another section.

33. In a machine for interleaving and folding paper towels and the like, the combination of a pair of cylinders, each having a gripper jaw and a folder blade, the folder blade on one cylinder fitting and coacting with the gripper jaw on the other cylinder, means for feeding towel sections between the cylinders so that each section overlies substantially one-half of an opposed section, the cylinders timed and the blades and jaws operated to cause each blade to engage a terminal of one section and the middle of an opposed section in a gripper jaw, and means to control the terminal of each section in its progress to and from the gripper jaws.

34. In a machine for folding and interleaving paper towels and the like, the combination of a pair of parallel juxtaposed cylinders, between which the sections to be interleaved are adapted to pass, each cylinder having a gripper jaw, a complementary folding blade on each cylinder coöperating with a corresponding gripper jaw on the other cylinder, transfer pins on each cylinder adjacent to the jaws to move one end of a section from one cylinder to the other, and means to control the opposed end of the sections.

35. In a machine for folding and interleaving paper towels and the like, the combination of a pair of parallel juxtaposed cylinders, between which the sections to be interleaved are adapted to pass, each cylinder having a gripper jaw, a complementary folding blade on each cylinder coöperating with a corresponding gripper jaw on the other cylinder, transfer pins on each cylinder adjacent to the jaws to move one end of a section from one cylinder to the other.

36. In a machine for folding and interleaving paper towels and the like, the combination of a pair of parallel juxtaposed cylinders, between which the towel sections to be folded and interleaved are adapted to pass in overlapped position so that one section overlies a back section substantially one-half of the latter, and devices on the cylinder including gripper jaws, folder blades, lead pins and transfer pins for controlling the terminals and central portion of the sections to deliver the sections interleaved and folded from the cylinders.

37. In a paper cutting and folding device, the combination of coöperating cylinders for folding and interleaving sheets of paper, gripper jaws on each of said cylinders, folder blades on each of said cylinders co-

operating with the jaws on the opposite cylinder, transfer pins on each of said cylinders adjacent to the jaws movable in and out to shift the sheets from cylinder to cylinder whereby the papers are delivered alternately by the cylinders in interleaved stacks.

38. In a paper cutting and folding machine, the combination of coöperative cylinders for folding and interleaving sheets of paper, gripper jaws on each of said cylinders, folder blades on each of said cylinders coöperating with the jaws on the opposite cylinder, transfer pins on each of said cylinders adjacent to the jaws movable in and out to shift the sheets from cylinder to cylinder whereby the papers are delivered alternately by the cylinders in interleaved stacks, separate cam mechanism for said gripper jaws and transfer pins, a severing device coöperating with each of said cylinders to cut the paper in proper lengths as the same is fed in a continuous web to the cylinders, pick-up pins movable in and out on each of said cylinders to engage with the leading end of the incoming web of paper, and cam mechanism for actuating said pick-up pins.

39. In a paper cutting and folding machine, the combination of coöperative cylinders for folding and interleaving sheets of paper, gripper jaws on each of said cylinders, folder blades on each of said cylinders coöperating with the jaws on the opposite cylinder, transfer pins on each of said cylinders adjacent to the jaws movable in and out to shift the sheets from cylinder to cylinder whereby the papers are delivered alternately by the cylinders in interleaved stacks, a severing device coöperating with each of said cylinders to cut the paper in proper lengths as the same is fed in a continuous web to the cylinders, pick-up pins movable in and out of each of said cylinders to engage with the leading end of the incoming web of paper.

40. In apparatus for folding and packaging paper sheets consisting of a pair of cylinders between which the sheets pass in overlapping position, folding grippers on each cylinder, folder blades on each cylinder coacting with the grippers on the opposed cylinder, means to lead the entering ends of the sheets to the grippers and means adjacent said grippers and folder blades respectively to transfer the trailing ends of the sheets to the opposite cylinder.

41. The combination of a pair of rotatable cylinders adapted to receive two webs of paper between them, one web entering over one cylinder and the other web entering over the other cylinder, cutters for each cylinder to cut the webs into sections, the cutters and cylinders timed to sever the webs into sections with the cuts in one web lying approximately midway of the cuts on

- the other web, folding means on each cylinder for each web section entering over it, means on each cylinder to guide the entering sections to the folding means on the 5 other cylinder, and means to transfer the loose ends of the sections to the opposite cylinder and maintain the loose ends in interleaved position with the complementary folded section.
- 10 42. Coöoperative folding and interleaving cylinders, a tucking member on each cylinder coöperating with a slot in the adjacent cylinder to fold the sheets in alternate interleaved fashion, and transfer pins adjacent to each slot and movable in and out on the cylinder to engage the sheets on both cylinders and carry them around to discharging position beneath the cylinders.
- 15 43. In combination, means for severing sheets of paper, and bringing said sheets into juxtaposed relation with substantially half of one sheet overlapping an equal amount of another sheet, means for subsequently folding the overlapped sheets along the median and marginal line to simultaneously produce a marginal fold on one sheet within the median fold of the overlapped sheet, said folding means interleaving said overlapping sheets so that each sheet when 20 folded incloses within its fold approximately one-half of another sheet.
- 25 44. Mechanism for interfolded sheets which consists in the combination of means which include a pair of closely arranged co-operating cylinders between which two webs of paper are brought together, means for cutting the webs into sections of desired length with the cut sections overlapping so that one section overlies substantially half 30 of an opposed section, means carried by the cylinders for interleaving the cut sections so that one leaf of one section will be infolded with the two leaves of an opposing section, and means for forming a reinforcing fold 35 along a terminal edge of each section.
45. In a paper interleaving machine, the combination of a pair of rotary cylinders between which paper sections are delivered in overlapped position for interleaving means on the cylinders for interleaving the sections so that substantially one-half of one section is interleaved with the opposed folded section, and means by which a marginal reinforcing fold is formed along the edge of the infolded leaf. 50
46. In a paper folding mechanism, a pair of coöordinate drums with sets of tucking jaws to receive the folds of sheets of paper, the set of each drum being arranged out of incidence with the set of the other drum, sets of co-acting folding means on each drum arranged intermediate said jaws, said folding means acting alternately and laying the sheets in interfolding zigzag relation, and transfer means on said drums for withdrawing the loose ends of the sheets from their carrying drum. 55
47. In a paper folding mechanism, a pair of coöordinate drums with sets of tucking jaws to receive the folds of sheets of paper, the set of each drum being arranged out of incidence with the set of the other drum, sets of co-acting folding means on each drum arranged intermediate said jaws, said folding means acting alternately and laying the sheets in interfolded zigzag relation, and transfer means on said drums for withdrawing the loose ends of the sheets from their carrying drum, the folding means being so disposed with relation to the tucking jaws 60 on their respective drums that a marginal flap is formed when the folding means act. 70
